UNITED STATES PATENT OFFICE.

JAMES R. McBURNEY, OF CAMBRIDGE, OHIO.

GLOVE.

Application filed September 13, 1926. Serial No. 135,179.

This invention relates to improvements in gloves and more particularly to a glove designed primarily for use by workmen although it may be used to advantage by motorists, and one of the objects of the invention is to provide a glove which will present all of the advantages and possess none of the disadvantages of a full leather or ordinary leather palm glove.

An all-leather glove presents the disadvantage that it is substantially non-yielding and stiff at its back and, therefore, freedom of movement of the fingers, particularly in grasping objects, is interfered with, and likewise such gloves are expensive to manufacture. A leather-palm glove is less expensive to manufacture but as such gloves are ordinarily manufactured they present the disadvantage that the finger fourchettes are of cloth as well as the back of the glove, and in the use of the glove, slight twisting of the finger stalls upon the fingers will bring the fourchettes into contact with the objects or material being handled, with the result that the fourchettes are soon worn through although the palm of the glove will show but little wear. Therefore, the invention has as another object to provide a glove having a leather palm and having its portions between the fingers of the glove likewise of leather so that the life of the glove will be greatly prolonged and in this connection the invention contemplates so forming the glove that the portions which are arranged between the fingers may be cut from sheet leather without any appreciable waste of material, so that the glove will be as inexpensive to manufacture as a leather-palm glove of the ordinary construction.

Another object of the invention is to provide a glove so constructed that it may be closed or completed by the formation of out-seams, thus obviating the tedious and time consuming operation of turning the gloves in the course of manufacture.

In the accompanying drawings:

Figure 1 is a front view of a glove constructed in accordance with the present invention.

Figure 2 is a view looking at the back of the glove.

Figure 3 is a horizontal sectional view taken substantially on the line 3—3 of Figure 2, looking in the direction indicated by the arrows.

Figure 4 is a similar view on the line 4—4 of Figure 2, looking in the direction indicated by the arrows.

Figure 5 is a vertical sectional view taken substantially on the line 5—5 of Figure 2.

Figure 6 is a plan view of the body blank of the glove.

Figure 7 is a plan view of the thumb blank.

Figure 8 represents a plan view of each of the blanks employed in producing the second finger stall of the glove, as well as a plan view showing the blanks assembled and united.

Figure 9 is a similar view illustrating each of the blanks employed in producing the third finger stall of the glove, and also illustrating said blanks assembled and united,

Figure 10 is a similar view illustrating each of the blanks employed in producing the little finger stall, and also showing said blanks assembled and united.

The glove embodying the invention comprises a palm or body blank indicated in general by the numeral 1, and including, in addition to the portion which is to constitute the palm of the glove, portions 2, 3, 4 and 5, the portions 2, 3 and 4 constituting the fronts of the little finger, third finger, and middle finger stalls of the glove, respectively, the portion 5 constituting the complete stall for the index finger and being, therefore, somewhat broader than the portions 2, 3 and 4 and being provided in its upper edge with a notch 6 and at its outer side at its juncture with the lateral edge of the body of the blank, with a base or shoulder portion 7. The blank 1 further includes a portion 8 defined by a straight incision 9 and a curvilinear incision 10, both extending inwardly from the base edge of the blank, and which portion constitutes the inner side of the thumb stall of the glove. The blank just described is made from leather as is also the blank shown in Figure 7, and indicated by the numeral 11, and which blank is of a marginal contour to match with the portion 8 of the blank 1 to form the outer side of the thumb stall of the glove. In uniting the thumb stall blank 11 to the blank 1, the portion 8 of the blank 1 is turned back in the usual manner and the marginal portions of the blank 11 are stitched to the edges of the incisions 9 and to the margins

105
110

of the said portions 8 of the blank 1 by an out-seam indicated by the numeral 12. The entire thumb of the glove is, therefore, of leather.

5 In forming up the forefinger portion of the blank, the blank is folded substantially on a straight line parallel to the incision 9 and extending through the notch 6, and the outer margin of the said portion 5 of the 10 blank is united to the margin of the said portion which is inwardly of the notch 6, the margin of the shoulder portion 7 extending within the crotch between the forefinger stall thus formed and the middle finger stall, the 15 seam uniting the margins of the said stall portions 5 and indicated by the numeral 13, being likewise an out-seam. It will be understood at this point that the first finger or index finger stall is, therefore, entirely of 20 leather and that the portion of the blank 1 between the incision 9 and the adjacent longitudinal or lateral edge thereof, which is indicated by the numeral 14, extends lengthwise down the back of the glove, this portion 25 being indicated by the numeral 15.

The second finger stall is formed from blanks such as shown in Figure 8, this figure also illustrating the blanks assembled and united. The numeral 16 indicates one of the 30 blanks which is to constitute the intermediate portion of the back of the stall and a portion of the back of the body of the glove, and this blank comprises an upper portion 17 and a lower narrower portion 18. The upper portion 17 is of conoidal section in shape and has curved lateral edges and a rounded upper end 19 while the lower portion 18 is tapered toward its lower end, the lateral edges of the two portions at their juncture being connected by diagonal edge portions 20. This blank is cut from canvas or other suitable cloth and is to be associated with the other blank which is shown in Figure 8, and which is indicated by the numeral 21. The blank 21 is cut from leather and comprises side portions 22 and an upper connecting portion 23, the portions 22 at their lower ends having curved diagonal edge portions 24. The inner or opposed lateral edges of the portions, indicated by the numeral 25, diverge downward to define an inverted substantially V-shaped notch, and the outer edges of the said portions 22 are preferably gradually curved outwardly, as indicated by the numeral 26, although not to any pronounced extent but sufficiently to provide the desired fullness at the backs of the respective finger stalls. As will be observed by reference to the right hand view of Figure 8 of the drawings, the leather blank 21 is disposed upon the broader portion 17 of the blank 16, in assembling the said blanks, and a line of stitching 27 is run through the blanks along the edges 25 of the blank 21, the diagonal lower edges 24 of the

portions 22 of the blank 21 being disposed in registration with the diagonal edge portions 20 of the blank 16.

The third finger stall is formed from blanks such as shown in Figure 9, this figure also illustrating the blanks assembled and united. The numeral 16' indicates one of the blanks which is to constitute the intermediate portion of the back of the stall and a portion of the back of the body of the glove. This blank 75 of fabric is substantially identical with the blank 16 with the exception that the diagonal edge portions 20' of the blank 16' are staggered with respect to each other, one of said edge portions being curved and the other being more or less straight. The other blank 21' of leather is substantially identical with the blank 21 with the exception that the side portions 22' of the blank 21' are of unequal length to correspond to the staggered relation of the edge portions 20' of the blank 16'. The view at the right of Figure 9 shows the blanks assembled. As will be observed, the diagonal lower edges of the side portions 22' of the blank 21' are disposed in registration with the diagonal edge portions 20' of the blank 16', and said blanks are united by a line of stitching 29 corresponding to the line of stitching 27.

The composite blanks shown in Figures 8 and 9, which respectively constitute backs of the second and third finger stalls of the glove, have the margins of their members 21 and 21' united by out-seams 30 to margins of the finger stall portions 3 and 4 of the blank 1, while the margins of the lower tapered portions 18 of the members 16 and 16' of said composite blanks are mutually united by inseams, below the bases of the finger stalls, as indicated by the numeral 31, these seams extending longitudinally of the back. In a like manner, one margin of the portion 18 of the blank 16, which constitutes a part of the second finger stall, is united by an in-seam 32 to the margin 14 of the portion 15 of the blank 1.

The little finger stall is formed from the blanks shown in Figure 10, one of which, indicated by the numeral 33, being cut from a sheet of canvas or other suitable fabric and comprising an upper portion 34 broadened at one side, as at 35, and a lower portion 36 which is slightly tapered toward its lower end. The upper portion 34 has one lateral edge coextensive with the corresponding lateral edge of the portion 36, and its opposite lateral edge curved away from its first mentioned edge, while the upper edge of the said portion 34 is of arcuate form, as indicated by the numeral 37. The last mentioned lateral edge of the portion 34 and the corresponding edge of the portion 36 are joined by a diagonal edge portion 38. The other blank is indicated by the numeral 39 and comprises side portions 115 120 125 130

40 and 41 and a connecting portion 42. This blank is cut from leather and the side portion 40 is relatively long and narrow and of substantially uniform width throughout its 5 length, whereas the portion 41 is somewhat broader and considerably shorter and has a diagonal lower edge 43, the opposing edges 44 of the portions 40 and 41 converging to define an inverted substantially V-shaped 10 notch. In assembling the blanks 33 and 39, the blank 39 is, as shown at the right of Figure 10, disposed upon one side of the blank 33 with the side portion 40 of the blank 39 extending longitudinally beyond 15 one lateral portion of the blank 33 throughout the length of the portion 36 of the latter blank and the corresponding marginal portion of the portion 34 of the blank 33, and with the diagonal edge 43 of the blank 39 20 registering with the diagonal edge portion 38 of the blank 33. Uniting the blanks is a continuous line of stitching 46 which extends along the opposing edges of the portions 40 and 41 of the blank 39 and the edge 25 portion 44 thereof and through the blank 33. In embodying the composite little finger blanks in the glove structure, the outer margin of the portion 36 of the member 33 is united by the adjacent in-seam 31 to the 30 third finger stall, as shown in Figure 2, and the relatively narrow projecting marginal portion of the member 40 of the blank 39, as well as the curved outer margin of said blank and likewise the outer margin of the 35 portion 41 of the blank, is united by an out-seam 47 to the corresponding marginal portions of the finger stall portion 2 of the blank 1, the portion 40 of the blank 39 extending downwardly throughout the length 40 of the back of the glove and being united by a continuation 48 of the out-seam 47, to the lateral margin of the blank 1 opposite the margin 14.

A wrist-band 49 of leather or other material found suitable for the purpose is united 45 to the base of the glove by a line of stitching 50 and is closed at the little finger side of the body of the glove by continuing the out-seam 48, or the wrist-band may be 50 united to the glove in any other manner found appropriate.

From the foregoing description of the invention it will be observed that the spaced portions 22 of the blank 21 and the spaced 55 portions 22' of the blanks 21' as well as the portion 41 of the blank 39 constitute the fourchettes of the glove between the finger stalls thereof and which portions are of leather and will, therefore, withstand the 60 same wear as the palm and the front portions of the finger stalls of the glove. Likewise, it will be evident that the member 40 of the little finger blank 39, which member extends along the outer side of the little 65 finger stall and the corresponding side of

the back of the body of the glove, constitutes a portion which is capable of withstanding the same wear as the palm of the glove. Therefore, as the fourchettes portions and the last mentioned portion of the glove are 70 subjected at times to considerable wear, the glove embodying the invention presents all of the advantages of a full leather glove.

It will also be observed by reference to Figure 2 of the drawings, that the portions 75 of the blanks constituting the backs of the finger stalls and which portions are those between the upper curvilinear margins of the said blanks 21 and 21' and the edge portions 25, in the instance of the second and 80 third finger stalls, and the upper curved margin and the edge portion 44 of the blank 39 of the little finger stall, serve as wear-resisting surfaces at the tips of the corresponding finger stalls, the canvas blanks 16, 85 16' and 33 serving to provide the desired yieldability to the bending of the fingers, which is one of the purposes of forming a work glove with a leather palm for a wear surface and with a canvas back as a flexible 90 back covering for the hand.

It will be further evident from the foregoing description of the invention that the object thereof is to provide a glove, all portions of which, subject to maximum wear, 95 are of a wear-resisting material and while ordinarily such portions of such gloves are made of leather, it will be understood that other wear-resisting material might be employed for the purpose, the remaining portions of the glove, eliminating from consideration of course, the wrist-band 49, being of a material which is pliable so as to afford freedom of movement of the fingers. Therefore, where, in the claim, the term "wear-resisting material" is employed, while it refers more specifically to leather, it is intended to cover any material which will possess wear-resisting qualities greater than the material which, in the foregoing description, 100 has been referred to as cloth or fabric.

Having thus described the invention, I claim:

A glove of the class described comprising an integral blank of leather including a 115 palm portion and front, second, third and little finger stall portions, and further including a first finger portion constituting the front, back and outer side of the first finger stall, and including also a portion 120 extending downwardly from the said first finger stall portion and constituting a wear-resisting portion at the back of the glove below the first finger stall, the said blank further including a front thumb stall portion 125 defined by spaced incisions and located laterally inwardly of the last mentioned portion, a back thumb stall portion of leather marginally united to the said front thumb stall portion and having a lower por- 130

tion marginally united to the lower portion of the first mentioned blank along the lines of the said incisions and extending to the lower margin of said first mentioned blank, blanks of leather having their outer lateral edges united to the margins of the second and third finger stall portions of the first mentioned blank and constituting the second and third finger stall fourchettes and also the backs of the tip portions of the respective stalls, a similar leather blank united at its outer lateral edges to the corresponding margins of the little finger stall por-

tion of the first mentioned blank and having a downward extension at one side united at its outer edge to the corresponding edge of the palm portion of the first mentioned blank and extending down the outer side of the back of the glove below the little finger stall, and blanks of more flexible material united marginally to the inner lateral margins of the last mentioned second, third and little finger stall blanks and also marginally to one another at the back of the glove. 15 29

In testimony whereof I affix my signature.
JAMES R. McBURNEY. [L. s.]
